(57) **CLAIM**

The ornamental design for a battery, as shown and described.

DESCRIPTION

FIG. 1 is a front, left, top perspective view of a battery of our new design, according to a second embodiment of the invention;

FIG. 2 is a rear, right, top perspective view thereof;

FIG. 3 is a rear, right, bottom perspective view thereof;

FIG. 4 is a front elevation view thereof;

FIG. 5 is a rear elevation view thereof;

FIG. 6 is a left side view thereof;

FIG. 7 is a right side view thereof;

FIG. 8 is a top view thereof; and,

FIG. 9 is a bottom view thereof.

The broken lines in the drawings represent portions of the battery that forms no part of the claimed design.

1 Claim, 9 Drawing Sheets
